(57) **CLAIM**

The ornamental design for a robotic pill dispenser, as shown and described.

DESCRIPTION

FIG. 1 is a top elevation view of a robotic pill dispenser;
FIG. 2 is a rear elevation view thereof;

FIG. 3 is a left side elevation view thereof; right side is a
mirror image; and,

FIG. 4 is a front side elevation view thereof.

The broken lines shown in FIGS. 1-4 show portions of the
robotic pill dispenser that form no part of the claimed
design.
